[57] CLAIM

The ornamental design for a table, as shown and described.

DESCRIPTION

FIG. 1 is a perspective view of a table showing my design;

FIG. 2 is a second perspective view of said design, taken from a point rotated 45° from and lower than that of FIG. 1;

FIG. 3 is an elevational view showing one of the four identical sides;

FIG. 4 is a top plan view looking down at the transparent top of said design;

FIG. 5 is a bottom plan view of said design.
